(57) CLAIM

The ornamental design for a garment, as shown and described.

DESCRIPTION

FIG. 1 is a front view of a garment according to the design;

FIG. 2 is a rear view thereof;

FIG. 3 is a right side view thereof;

FIG. 4 is a left side view thereof;

FIG. 5 is a front perspective view thereof;

FIG. 6 is a rear perspective view thereof; and,

FIG. 7 is a front view thereof shown in an environment of use.

The portions of the garment shown in dash-dash broken lines in FIGS. 1-7 do not form part of the claimed design. The dash-dash broken line showing of the feet, arms, and torso in FIG. 7 is for the purpose of illustrating portions of the environmental structure and forms no part of the claimed design. The dot-dash broken lines shown on the legs and at the waistband of the garment in FIGS. 1-7 are for illustrating the boundary of the design only and do not form part of the claimed design.
